DESIGN FOR A BRACELET OR SIMILAR ARTICLE

John G. Siska, Cresskill, N. J., assignor to Jacques Kreisler Manufacturing Corporation, North Bergen, N. J.

Application January 27, 1947, Serial No. 136,445

Term of patent 7 years

(Cl. D45—4)

To all whom it may concern:

Be it known that I, John G. Siska, a citizen of the United States of America, residing at Cresskill, county of Bergen, and State of New Jersey, have invented a new, original, and ornamental Design for a Bracelet or Similar Article, of which the following is a specification, reference being had to the accompanying drawing, forming a part thereof.

Fig. 1 is a front elevational view of a bracelet showing my new design;

Fig. 2 is a front elevational view showing the bracelet in slightly extended condition;

Fig. 3 is an edge view of the bracelet as viewed in the direction of the arrow 3 in Fig. 1;

Fig. 4 is a rear view of the bracelet;

Fig. 5 is a view showing a few of the top elements of the bracelet on an enlarged scale;

Fig. 6 is an enlarged section taken on the line 6—6 of Fig. 1.

The center portion of the bracelet in Figs. 2, 3 and 4 is shown broken away for illustrative purposes as indicated by the dot-and-dash lines.

I claim:

The ornamental design for a bracelet or similar article, as shown and described.

JOHN G. SISKA.
